UNITED STATES PATENT OFFICE.

RICHARD LORENZ, OF RUMMELSBURG, GERMANY.

WIRE-DRAWING MACHINE.

No. 817,979.

Specification of Letters Patent.

Patented April 17, 1906.

Application filed August 3, 1905. Serial No. 272,545.

To all whom it may concern:

Be it known that I, RICHARD LORENZ, a subject of the King of Prussia, German Emperor, residing at Rummelsburg, near Berlin, 5 Prussia, Germany, have invented a new and useful Improved Wire-Drawing Machine, of which the following is a description.

The present invention relates to machines for simultaneously drawing several wires; 10 and it consists of the details of construction as hereinafter set forth.

In order to render the present invention easily intelligible, reference is had to the accompanying drawings, in which—

15 Figure 1 is a front view of the machine. Figs. 2 and 3 are side views of the supports for the diamond-holders. Fig. 4 is a top view of the support, and Fig. 5 a diagram of the guiding of the wires.

20 The wire I is guided around the guiding-roller 2, loosely mounted on the shaft 1, and passes through the drawing-iron 3, Figs. 2, 3, and 4, from here two times around the drawing-roller 5, secured fast on the shaft 4, 25 and then to the next higher guiding-roller 6 of the larger set of guiding-rollers A. After the wire I has successively passed all the drawing-irons of the rear drawing-mill B and been guided around all the guiding and 30 drawing rollers of the set of rollers A and C, respectively, it goes at 20 to a drum, similar to the drum 7 of the next drawing-mill. The wire I', coming from the uppermost guiding-roller of the preceding drawing-mill, similar 35 to that herein described, is correspondingly wound on the drum 7, which is fast on the shaft 1. The wire I I is at first guided around the smallest loose roller 8 of the set of guiding-rollers D, passes from there through the 40 lowermost drawing-irons of the front row E, then to the lowermost roller 9 of the drawing-mill F, and finally, after having passed the several drawing-irons of the front row E, arrives at the drum 10, which is fast on the 45 shaft 4.

The drawing-irons are rotated as usual and driven in the following manner, Figs. 2, 3, and 4: The spindle 11, which is driven by a pulley arranged below the working table, 50 carries at its head a worm 12, which engages with a worm-wheel 13. The shaft of the worm-wheel 13, which is mounted in the bearing 14, carries at the other end of the bearing a spur-wheel 15, which in turn engages with the spur-wheel 16 of the uppermost drawing-iron holder of the front row E.

The uppermost spur-wheel 16 engages in turn the spur-wheel of the next following drawing-iron holder, and this spur-wheel engages the next following spur-wheel, and so on, so that 60 thus the entire front drawing-iron row E is rotated.

The rear drawing-iron row B is rotated in the following manner: At the rear side of all the front wheels of the front drawing-iron 65 row E conical wheels are arranged, which are in engagement with conical wheels at the drawing-iron row of the rear row B. For example, the conical wheel 17 at the uppermost spur-wheel 16 is in engagement with 70 the conical wheel 18 of the uppermost drawing-iron holder 19 of the rear part of the row B. The second uppermost wheel of the front row E drives in turn the second uppermost wheel of the rear row B by means of 75 conical wheels, and so on. Instead of the conical wheels spur-wheels may be employed.

The distance apart of two adjacent rollers of the same roller set—for instance, of the rollers 2 and 6—over which the same wire I 80 passes is governed by the size of the drawing-iron holder. This distance apart cannot be diminished, since the size of the drawing-iron holders cannot be reduced. In this invention, however, parallelly to the first row 85 of drawing-iron holders for the wire I a second row of drawing-iron holders is arranged, through which the wire I I passes, which, as herein described, is guided over special guiding and drawing rollers lying between those of 90 the first wire. Thus the room which has hitherto been used for the production of a single wire serves now for the double production.

I claim as my invention—

1. In combination two sets of conical guiding-rollers, those of one set being larger in diameter than and alternating with the corresponding guiding-rollers of the other set, two sets of conical drawing-rollers, those of one set being larger than and alternating with 100 the corresponding rollers of the other set, all of the guiding-rollers being on one axis and all of the drawing-rollers on another axis and two sets of drawing-irons arranged between the guiding and drawing rollers, said sets of 105 drawing-irons being in two parallel rows and in the same plane, substantially as described.

2. In combination two sets of conical guiding-rollers, those of one set being larger in diameter than and alternating with the corresponding guiding-rollers of the other set, two sets of conical drawing-rollers, those of one 110

- set being larger than and alternating with the corresponding rollers of the other set, all of the guiding-rollers being on one axis and all of the drawing-rollers on another axis,
5 two sets of drawing-irons arranged between the guiding and drawing rollers, said sets being in two parallel rows and in the same plane and means for rotating said drawing-iron consisting of intermeshing gears on one row

and intermeshing gears between the opposing 10 irons of the two rows.

In testimony whereof I affix my signature in the presence of two witnesses.

RICHARD LORENZ.

Witnesses:

HENRY HASPER,
ALFRED M. LISBON.
